CASE CONSTRUCTION FOR BREAD TOASTERS

Filed Feb. 25, 1949

ROBERT A. MILLER

Cassell & Lagan

UNITED STATES PATENT OFFICE

2,564,368

CASE CONSTRUCTION FOR BREAD
TOASTERSRobert A. Miller, Grand Haven, Mich., assignor to
Camfield Manufacturing Company, Grand
Haven, Mich., a corporation of Michigan

Application February 25, 1949, Serial No. 78,406

5 Claims. (Cl. 99—401)

1

My invention relates to case construction for bread toasters and has for an object to provide a construction whereby the case of the toaster may be constructed in two sections and the sections secured together without visible attaching means.

Another object of the invention resides in providing a construction whereby the frame of the toaster is used for securing the case sections together.

A still further object of the invention resides in providing a case construction utilizing an upper case section having a bread receiving opening therein and in providing attaching means for securing the sections together and accessible through said opening.

A feature of the invention resides in constructing the upper case sections with ears at the ends of said opening and adapted to overlie portions of the frame of the toaster and to further provide fasteners engaging said ears and said frame.

Other objects of the invention reside in the novel combination and arrangement of parts and in the details of construction hereinafter illustrated and/or described.

In the drawings:

Fig. 1 is a plan view of a case for bread toasters illustrating an embodiment of my invention.

Fig. 2 is an elevational view of the structure shown in Fig. 1, partly in section, and taken on line 2—2 of Fig. 1.

Fig. 3 is a cross sectional view taken on line 3—3 of Fig. 1.

My improved case construction for bread toasters comprises a case indicated in its entirety by reference 10. This case consists of an upper case section 11 and a lower case section 12 connected together along a horizontal line located intermediate the upper and lower portions of the case.

The lower case section 12 has a body portion 13 which extends circumferentially of the case and which has ends 14 and sides 15. The lower marginal portion of section 12 extends inwardly as indicated at 15 and is provided with an upstanding part 24 disposed substantially parallel with the body of the case. Issuing inwardly from this part of case section 12 is a flange 16 disposed entirely upon the interior of the case and extending circumferentially about the same.

Mounted on the flange 16 is a frame 17 which includes two end plates 18 and 19 and a top 20 connecting the same together as best shown in Fig. 2. This frame supports the bread ovens and heaters and other mechanism of the toaster.

2

Those parts, however, forming no particular feature of the instant invention have not been illustrated in the drawings. These end plates and the manner of supporting the same being identical, only the end plate 18 will be described in detail. The end plate 18 has a flange 21 extending outwardly from the lowermost portion of the same and which extends across the opposite portions of the flange 16 of case section 12 as illustrated in Fig. 3. The flange 21 is formed with bosses 22 which are threaded to receive screws 23. These screws extend through the flange 16 and are disposed beneath said flange where the same are readily accessible for the purpose of attaching the frame to the lower case section 12. The upstanding part 24 serves to offset the flange 16 above the lowermost portion of the case in order to conceal the screws 23. The end plates 18 and 19 extend upwardly beyond the lower case section 12 and into the upper case section 11.

The upper case section 11 is dome-shaped in form having a top 25, end walls 26 and side walls 27. These walls are continuous and have a lower marginal portion 28. The upper part of the lower section 12 is constructed with a lip 29 which is offset to form a recess 31 in which the marginal portion 28 of case section 11 is adapted to be received. When the upper case section 11 is assembled on the lower case section 12, only a single line of joinder 32 appears between the two case sections. The upper case section 11 is provided with two openings 33 through which the bread may be introduced into the bread ovens of the toaster. The openings 33 are bounded by flanges 34 which extend along the sides of the said openings. At the ends of the openings 33 are formed ears 35 which are situated opposite one another and which incline downwardly of the ends of said openings. These ears overlie inclined portions 36 on the end plates 18 and 19 of the frame 17. The said portions are formed with bosses 37 which are threaded to receive screws 38. The screws 38 extend through the ears 35 and are accessible from the bread openings 33. It will thus be seen that the two sections of the case are held together by the frame 17 and that no visible means of attachment appears upon the exterior of the case.

Plastic ornaments may be attached to the ends of the lower case section 12 by means of screws 41 tapped into said ornaments and extending through the ends 14 of said section. Likewise feet 42 may be attached to the portion 15 of the lower case section 12 for supporting the bread

toaster above the level of the table on which the case rests.

The method of using the invention is obvious. The various parts of the toaster mechanism including the toast oven and timing mechanism are first mounted on the frame 17 in the customary manner. The said frame is then attached to the lower case section 12 by means of the screws 23. The upper section 11 is next applied by directing the marginal portion 28 into the recess 31. 10 The section 11 is then attached to said frame by means of the screws 38.

The advantages of the invention are manifest. The construction is extremely simple making it possible to construct the case of two stamped pieces. Attachment of the parts of the case together is accomplished through the frame for the toaster mechanism and the securing of the upper case section is procured by fastening means accessible through the bread openings in the case. The screws so used are below the upper surface of the toaster case and are hence quite inconspicuous. My improved toaster case can be constructed at an extremely economical cost.

Changes in the specific form of my invention, as herein described, may be made within the scope of what is claimed without departing from the spirit of my invention.

Having described my invention, what I claim as new and desire to protect by Letters Patent is:

1. In a case construction for bread toasters, a lower case section, supporting means extending inwardly from the lower portion thereof, a frame attached to said supporting means and extending upwardly above the same, an upper case section superimposing said lower case section and having a bread receiving opening therein, oppositely disposed ears on said upper case section overlying portions of said frame and disposed at said bread receiving opening, and fasteners engaging said ears and said frame and urging said upper case section toward said lower case section to hold said case sections in cooperative relationship, said fasteners being accessible through said bread receiving opening, said ears and fasteners being disposed wholly within the confines of said case section.

2. In a case construction for bread toasters, a lower case section, supporting means extending inwardly from the lower portion thereof, a frame attached to said supporting means and extending upwardly above the same, an upper case section superimposing said lower case section and having a bread receiving opening therein, oppositely disposed ears on said upper case section overlying portions of said frame and disposed at said bread receiving opening, screws extending through said ears and engaging said frame and urging said upper case section toward said lower case section to hold said case sections in cooperative relationship, said screws being accessible through said bread receiving opening, said ears and screws being disposed wholly within the confines of said case section.

3. In a case construction for bread toasters, a lower case section, supporting means extending inwardly from the lower portion thereof, a frame attached to said supporting means and extend-

ing upwardly above the same, an upper case section superimposing said lower case section and having an elongated bread receiving opening therein, oppositely disposed ears on the upper case section and disposed at the ends of said opening, said ears overlying portions of said frame and fasteners extending through said ears and engaging said frame and urging said upper case section toward said lower case section to hold said case sections in cooperative relationship, said fasteners being accessible through said bread receiving opening, said ears and fasteners being disposed wholly within the confines of said case section.

4. In a case construction for bread toasters, a lower case section, supporting means extending inwardly from the lower portion thereof, a frame attached to said supporting means and extending upwardly above the same, an upper case section superimposing said lower case section and having an elongated bread receiving opening therein, oppositely disposed ears on the said upper case section and located at the ends of said bread receiving opening, said ears extending angularly downward from the uppermost portion of the case and overlying portions of said frame and fasteners engaging said ears and frame and urging said upper case section toward said lower case section to hold said case sections in cooperative relationship, said fasteners being accessible through said bread receiving opening, said ears and fasteners being disposed wholly within the confines of said case section.

5. In a case construction for bread toasters, a lower case section, supporting means extending inwardly from the lower portion thereof, a frame attached to said supporting means and extending upwardly above the same, an upper case section superimposing said lower case section and having an elongated bread receiving opening therein, oppositely disposed ears on the said upper case section and located at the ends of said bread receiving opening, said ears extending angularly downward from the uppermost portion of the case and overlying portions of said frame and screws extending through said ears and screwed into said frame and urging said upper case section toward said lower case section to hold said case sections in cooperative relationship, said screws being accessible through said bread receiving opening said ears and screws being disposed wholly within the confines of said case section.
